PERCUSSION FUSE

Glaf Rasmussen, Dayton, Ohio, assignor to General Motors Corporation, Detroit, Mich., a corporation of Delaware

Application December 7, 1942, Serial No. 468,032

7 Claims. (Cl. 102—70)

This invention relates to improvements in percussion fuses particularly adapted to be used to fire and explode land mines.

It is among the objects of the present invention to provide a percussion fuse of simple structure and design which is adapted to fire a land mine only in response to the application of a predetermined load thus eliminating the explosion of the mine accidentally or by the application of loads below the predetermined value.

A further object of the present invention is to provide a percussion fuse which cannot be detected by the usual electro-magnetic detecting devices.

Further objects and advantages of the present invention will be apparent from the following description, reference being had to the accompanying drawing wherein a preferred embodiment of the present invention is clearly shown.

In the drawing:

Fig. 1 is a plan view of one form of the present invention.

Fig. 2 is a sectional view taken along the line 2—2 of Fig. 1.

Fig. 3 is a plan view of a modified form of the present invention, and

Fig. 4 is a sectional view taken along the line 4—4 of Fig. 3.

Referring to the drawing and more particularly to the Figs. 1 and 2 thereof, the numeral 20 designates the dish-shaped base portion of the percussion fuse box. This may be made of any suitable non-metallic material but for large quantity production purposes a moldable plastic such as Bakelite or the like is preferable inasmuch as no finishing processes are necessary after the piece is taken from the mold. The base is provided with a knob-like extension 21 having a central passage 22 both ends of which open into larger recesses in the wall of the base. Recess 23 is at the inner end of passage 22 and the recess at the outer end of said passage receives the non-metal tube 30 containing the primer charge 31.

The firing pin 25, made of any suitable non-metallic material such as a plastic, ceramic or glass comprises a comparatively strong body portion 26 which slidably fits into the passage 22 and a thin, integral, frangible flange 28 which normally rest upon the inner surface of the base wall about said passage. The inner end of the body portion 26 of the firing pin is pointed and normally spaced from the primer charge as shown in Figs. 2 and 4.

Numerals 32 designates a non-metallic reed

which is suspended between two opposite walls 33 and 34 of the dish-shaped base portion 20. Any hard wood may be used to make a satisfactory, substantially stiff reed. One end of the reed has an opening which fits over the nipple 35 on the base portion 20 thereby securing this end of the reed to the base. The opposite end of the reed merely rests upon the upper surface of the base wall 30 so that a wooden striker block 36 attached to the reed, normally is directly above the firing pin 25 and spaced therefrom.

The casing of the percussion fuse has a lid or cover 40 fitting into a peripheral recess provided on the base 20. This cover 40 may be secured to the base by cementing or any other similar manner as long as no metal posts are used as fasteners. A passage or opening 41 is provided in the cover for slidably receiving the piston plug 42 the outer end of which extends beyond the outer surface of the cover. Piston plug 42 is held suspended in the cover opening 41 by a frangible, annular flange 43 formed integral with the piston plug and resting in an annular recess provided in the outer surface of the cover surrounding opening 41. A depending projection 47 on the piston plug 42 normally engages the reed 33 near its end anchored to the nipple 35 of the base 20. Like the cover and base, the piston plug 42 is made of non-metallic material.

In the Figs. 3 and 4, a modified form of the invention is illustrated. The base portion 120 of the percussion fuse box is somewhat like the base portion 20 shown in Fig. 2. It has a knob like extension 121 in which a firing pin 125, identical with firing pin 25, is carried. This firing pin 125 has a frangible flange 128. A primer charge 131, in container tube 130 is located in alignment with firing pin 125 so that it may be fired by said pin. A reed 132 anchored at one end to the nipple 135 on the base has its other end resting upon the wall 133 of said base. This reed 132 has a striker block 136 normally spaced from and positioned directly above the firing pin 125.

The cover or lid 140 of the modified form of percussion fuse differs, however, from the lid 40 of the device shown in Fig. 2. This cover 140 is a single piece having a peripheral recessed flange 141 fitting upon and secured to the peripheral edge of the base 120. Cover 140 has two inwardly extending lugs 142 and 147. The lug 142 has a rounded end which hingedly fits into a socket like indent 143 in the upper surface of the base wall 133. The lug 147 normally rests upon the reed 132 adjacent its anchored

end. The portion of the cover between lugs 142 and 147 is substantially thick to provide strength and rigidity while on the contrary a peripheral area designated by the numeral 144 is of a comparatively thinner construction so as to provide a frangible area in the cover which is sufficiently strong to support a certain load but which will fracture in response to a predetermined load in excess of said certain load applied to the percussion fuse box.

Like the percussion fuse of Fig. 2, the modified form of Figs. 3 and 4 has its base and cover made of non-metallic material, preferably a moldable plastic, its firing pin of glass and its reed of a hard wood. No metal whatsoever is used in any part of the device. The purpose of this is to eliminate the possibility of its detection by any type of electrical detector adapted to indicate the presence of a metal.

When the percussion fuse is in operative connection with a mine, particularly a land mine, the fuse itself is buried close under the surface of the ground so that any loads passing over it is applied to the cover of the percussion fuse. The piston-plug 42 or the cover 140 may have their frangible portions so designed and constructed as to be able safely to support any chosen load without fracturing. For instance these members 42 and 140 may have their frangible areas or sections 43 and 144 respectively so thick as to support a load of 600 pounds without fracturing. However if a load in excess of 600 pounds would be applied to said members their frangible sections 43 and 144 respectively would fracture.

When the section 43 of the piston-plug 42 fractures in response to the application of a certain load, the piston-plug 42 is forced downwardly through passage 41 and thus lug or projection 47 presses upon and flexes the reed 32 downwardly. As the stiff reed 32 is bowed or flexed downwardly energy is built up therein which is suddenly released when the free end of said reed 32 slides from the wall 33. When the striker block 36 strikes the firing pin 25 its frangible flange 28 will be shattered and then the firing pin is quickly forced outwardly through the passage 22 into firing engagement with the primer charge 31, exploding the mine.

In the device shown in Figs. 3 and 4 the load applied to cover 140 fractures its frangible section 144 and moves the thicker part thereof downwardly said part pivoting about the lug 142 resting in the socket 143 of wall portion 133. Lug 147 of the cover bows reed 132 which, when it passes the ledge of wall 133 thrusts striker block 136 against the firing pin 125, breaking its flange 128 and urging the pin 125 into firing engagement with the primer charge 130. It will be noted that the design and construction of the two forms of percussion fuses illustrated precludes the entrance of dust and dirt into the interior thereof inasmuch as the two parts of the container, that is, the base and cover are sealed together. This provides for a safe and positively acting percussion fuse. Either device may easily be arranged for any selected load at which the mine is to be exploded. For a heavier load a piston plug with a heavier flange 43 is placed in the cover opening 41 and in the other structure a cover having a heavier frangible section 144 is placed on the base portion 120 and sealingly secured thereto.

When buried in the ground so that the percussion fuse is just beneath the surface, no way of detecting its presence excepting perhaps by the

hit or miss probing method is possible. The use of an electromagnetic detector is futile for neither the percussion fuse nor mine has any metal part that would be indicated by such a detector.

The design and construction of the two forms of devices is simple for one consists of five parts four of which may be molded, the other consists of four parts three of which are shown as molded construction.

10 While the embodiment of the present invention as herein disclosed, constitutes a preferred form, it is to be understood that other forms might be adopted, all coming within the scope of the claims which follow.

15 What is claimed is as follows:

1. A completely non-metallic percussion fuse comprising in combination, a non-metal container a portion of which is frangible under a predetermined load; a non-metal firing pin in said container provided with a fragile portion which holds said pin in normal position; and a non-metal, stiff reed suspended within the container and adapted to be flexed and released to fracture the fragile portion of the firing pin and actuate said pin in response to fracture of the container portion by the application of said load.

2. A complete non-metallic percussion fuse comprising in combination, a plastic container having a portion frangible under a predetermined load; a glass firing pin in said container, said pin having a thin flange holding the pin in normal position in said container; and a stiff, wood reed suspended within the container and adapted to be flexed to strike the firing pin, break its flange and quickly thrust said pin outwardly from said container in response to fracture of the frangible container portion.

3. A percussion fuse comprising in combination, a non-metal housing provided with an opening in its one wall; a non-metal firing pin in said opening, said pin having a frangible flange engaging the housing to support the firing pin; a non-metal reed supported only at its ends in the housing, one end being anchored to the housing; and a non-metal cover for the housing, said cover having an area of reduced thickness adapted to be fractured in response to a predetermined load being applied upon the cover and cause movement of the cover toward the housing, said cover having a lug normally engaging the reed.

4. A percussion fuse comprising in combination, a non-metal box including a main body portion and a cover having a portion frangible at a predetermined applied load; a non-metal firing pin slidably fitting in an opening in said body portion, said pin having a frangible flange holding the pin in normal position; a non-metal reed suspended only between two opposite walls of the body portion, one end of the reed being anchored to the one body portion wall; and means on the cover, normally engaging the reed and adapted to flex the reed and thereby disengage its one end from the body portion wall whereby said reed will strike the firing pin and fracture its flange to thrust the firing pin outwardly through the body portion as the cover is fractured by the application of said predetermined load.

5. A percussion fuse comprising in combination, a non-metal housing consisting of a base and a frangible cover; a firing pin of non-metallic material slidably held in a passage in a wall of the base said pin having a frangible flange normally holding the pin within said passage; a non-metal, stiff reed suspended only at its ends

between two walls of the base, so that one end of the reed lies above and is spaced from the firing pin, the other end of said reed being anchored to its base wall; a lip on said cover, hingedly engaging the base providing a pivot member about which the cover moves relatively to the base when said cover is fractured by the application of a predetermined load; and a depending lug on said cover normally engaging the reed and adapted to flex said reed to cause it to strike the firing pin and fracture its flange as said pin is thrust outwardly through the passage in the base in response to fracture of said cover and its movement toward the base.

6. A completely non-metallic percussion fuse comprising in combination, a box of plastic material consisting of a base portion and a cover, a portion of which is frangible when a predetermined load is placed on said cover; a glass firing pin slidably supported within a passage in one wall of the base portion, said firing pin having a comparatively thin, fragile flange by which the pin is held in normal position within said passage; a reed of comparatively hard but resilient wood suspended by its two ends in the base portion, one end directly over the firing pin

and spaced therefrom; and means on the cover normally engaging the reed and adapted to flex it for striking the pin, fracturing its flange and thrusting it outwardly through the passage when the cover is fractured by said load.

- 5 7. A percussion fuse comprising in combination, a non-metallic container consisting of a base and a lid, each of which is provided with a passage; a non-metallic firing pin in the passage of the base, said pin having a frangible flange normally holding the pin within the passage of the base; a non-metallic, substantially stiff reed suspended in the base, one end of said reed being anchored to a wall of the base, the other end resting on the opposite wall of the base and directly above the firing pin; and a non-metallic plug slidably fitting in the passage of the lid and having a frangible annular rim engaging the lid to hold the plug in said passage, 15 said plug having a depending lug normally engaging the reed and adapted to flex said reed and thrust it against the firing pin to break its flange and quickly push said firing pin outwardly in its passage as the rim of the plug is fractured 20 and the plug is pushed downwardly into the lid.
